Specification of Letters Patent.

Patented June 6, 1916.

Application filed June 27, 1910. Serial No. 569,206.

To all whom it may concern:

Be it known that we, CECIL HAMELIN TAYLOR and HOWARD E. COFFIN, citizens of the United States of America, residing at 5 Detroit, in the county of Wayne and State of Michigan, have invented certain new and useful Improvements in Explosion-Engines, of which the following is a specification, reference being had therein to the accompanying drawings.

The invention relates to explosion engines and more particularly to the type of multi-cylinder engines provided with rotary valves.

15 The invention consists in various features of construction as hereinafter set forth. In the drawings; Figure 1 is a vertical longitudinal section through the engine; Fig. 2 is a cross section on line X—X, Fig. 1; Fig. 20 3 is a section on line Y—Y, Fig. 1; Fig. 4 is a sectional plan view; and Fig. 5 is a perspective view of the valve driving mechanism.

25 A, A', etc., are series of engine cylinders preferably integral with each other, and B is the crank case therefor. C is a crank shaft within this case having journal bearings D at opposite ends thereof.

30 E are rotary valves of the disk type arranged in the upper ends of the respective cylinders and mounted shafts F passing outward axially therefrom.

One of the features of our invention is the 35 construction of mechanism for driving the rotary valves and also for driving various accessories of the engine—such as the water pump, oil pump, magneto, etc., as follows: Each of the shafts F has mounted upon its 40 upper end a gear wheel G, and these gears for the valves of the various cylinders are in mesh with each other forming a continuous train. As in engines of the four-cycle type, the speed of rotation of the valve shaft with respect to that of the crank shaft is one-to-45 two, which necessitates a step-down gear train from the crank to the series of intermeshing gears. It is desirable to restrict the dimensions of the engine casing as much as possible, and, therefore, difficulties are 50 encountered in the arrangement of this step-down train without complications or excess of the space limits determined upon. We have accomplished the desired result by transmitting the motion of the crank shaft to a

superposed transversely-arranged horizontal 55 shaft H, and from the latter to a vertical shaft I offset from the plane of the crank shaft. Pairs of spiral gears J J' K K' are employed to connect the crank shaft with the horizontal shaft, and the latter with the 60 vertical shaft, and a pinion L at the upper end of the vertical shaft engages one of the gears in the train operating the valves. This transmission has the advantage—first, that the offset relation of the vertical shaft 65 does not increase the length of the engine casing, as would be the case if it were in the plane of the crank shaft; second, the proper ratio in the gearing may be obtained with greater convenience and range in selection, in the sizes of the gears; both the vertical shaft and the horizontal shaft are free at the ends for attachment with other mechanism, and may be employed for driving the accessories. Thus, as shown in Fig. 75 2, the right hand end of the horizontal shaft H has a coupling H' thereon for driving the magneto. The right hand end of the same shaft is used for driving the water pump, which, as shown, at M, is arranged 80 near the bottom of the crank case, and is connected to the horizontal shaft by the vertical shaft M' and bevel gears M'. Again, the vertical shaft I is connected at its lower end with the oil pump N, which is arranged 85 at the bottom of the crank case, and has its actuating shaft N alined with and coupled to the shaft I. As has been stated, the rotary valves E are arranged at the upper ends of the engine cylinders, and control inlet 90 and exhaust ports therein, which ports connect with induction and exhaust passages preferably formed in the integral head of the cylinder. Adjacent valves rotate in opposite directions by reason of the intermeshing of their drive gears, and this facilitates the arrangement of the common inlet and exhaust passages O and P for said cylinders, as shown in Fig. 4. These passages, as well as a water jacket which surrounds the bearing for the stem or shaft of the valve, are 95 all formed in integral construction.

The valve shafts F are preferably journaled in bearings upon opposite sides of the gear wheels G, and, as shown, the outer 100 bearings are formed in a cap Q or cover of the valve case.

R are the bearings, preferably ball bear-

ings, which are arranged in recessed bosses R' in the cap Q.

Q' are bolts for securing the cap to the engine casing.

5 In operation, the motion of the crank shaft is communicated through the spiral gears J J' to the horizontal shaft H, and from the latter through the spiral gears K K' to the vertical shaft I. This, through the pinion L, communicates movement to the series of intermeshing gears G for operating the valves. At the same time, the various accessories are driven, and the entire driving train is arranged compactly without increasing the necessary dimensions of the engine casing.

What we claim as our invention is:

1. In an engine, the combination with the cylinder, of a rotary valve having its axis parallel to the axis of the cylinder, a transmission shaft parallel to the axis of the cylinder and in a plane noncoincident with the plane of the crank shaft, a gearing connecting said transmission shaft with the crank shaft and with the valve, and an accessory to the engine driven from one end of said transmission shaft.

2. In an engine, the combination with an engine cylinder, and a crank shaft, of a rotary valve for said engine cylinder, a drive train between said crank shaft and rotary valve, including a plurality of shafts in noncoincident planes, and a plurality of accessories driven from the intermediate shafts.

3. In an engine, the combination with the engine cylinder and crank shaft, of a rotary valve in said cylinder, a transmission shaft geared to said rotary valve and extending parallel to the axis of the cylinder in a plane noncoincident with that of the crank shaft, a bearing for the crank shaft, a gear mounted on said crank shaft and recessed to surround said bearing, a shaft in the plane of said gear transverse to the crank shaft and to the transmission shaft, and spiral gears connecting the last-mentioned shaft with the gear on the crank shaft and the shaft parallel to the axis of the engine cylinder.

4. In an engine, the combination with a crank shaft and cylinder, of a rotary valve having its axis coincident with the axis of the cylinder, a gear wheel for driving said valve, a pinion intermeshing with said gear wheel, a shaft parallel to the axis of the cylinder on which said pinion is mounted, said shaft being arranged in a plane noncoincident with the plane of the crank shaft, a shaft transverse to the crank shaft and the shaft parallel to the axis of the cylinder, a bearing for the crank shaft extending outward beyond the plane of said transverse shaft, and spiral gears connecting the crank shaft to the transverse shaft and the latter to the shaft parallel to the axis of the cylinder.

5. In an engine, the combination with a plurality of integral cylinders, of rotary valves in said cylinders adjacent the integral head thereof, stems on said valves extending through said head, intermeshing gears on said stems, common inlet passages for each pair of cylinders formed in said head, a common exhaust passage for the entire series of cylinders formed in said head, and a water jacket surrounding said inlet and exhaust passages and the stems of said valves.

6. In an engine, the combination with an engine cylinder having a port therein, a rotary valve controlling said port, a shaft extending longitudinally of the cylinder, a drive connection between the upper end of said shaft and said valve, a crank shaft, a gear thereon, an intermediate transmission shaft driven from said gear, drive connections between said intermediate shaft and said first mentioned shaft, said transmission shaft having an extension, and an accessory to the engine driven from said extension.

7. In an engine, the combination with an engine cylinder, having a port therein, a rotary valve controlling said port, a shaft extending longitudinally of the cylinder, a drive connection between the upper end of said shaft and said valve, a crank shaft, a gear thereon, an intermediate transmission shaft driven from said gear, drive connections between said intermediate shaft and said first mentioned shaft, and accessories to the engine driven from both ends of the intermediate transmission shaft.

8. In an engine, the combination with an engine cylinder, having a port therein, a rotary valve controlling said port, a shaft extending longitudinally of the cylinder, a drive connection between the upper end of said shaft and said valve, a crank shaft, a gear thereon, an intermediate transmission shaft driven from said gear, drive connections between said intermediate shaft and said first mentioned shaft, a shaft driven from one end of the intermediate shaft, and an accessory driven from said last mentioned shaft.

9. In an engine, the combination with a plurality of integral cylinders, of rotary valves in said cylinders adjacent the head thereof, stems on said valves extending through the head, intermeshing gears on the stems, common inlet passages for each pair of cylinders formed in said head, and a common exhaust passage for the entire series of cylinders formed in the head.

10. In an engine, the combination with a plurality of integral cylinders having ports through the heads thereof, rotary valves controlling said ports, intermeshing gears

on the valve stems, common inlet passages for each pair of cylinders formed in the head, and a common exhaust passage for the entire series of cylinders formed in said head.

5 11. In an engine, the combination with an engine cylinder, of a rotary valve having a stem extending out through the head of said cylinder, a gear mounted on said stem, a detachable cap forming a housing for said gear, and a journal bearing for the outer end of said stem arranged within and inclosed by the detachable cap.

10 12. In an engine, the combination with a plurality of cylinders, rotary valves for said cylinders having operating stems extending out through the walls of the cylinders, intermeshing gears on said stems, a detachable

cap housing said gears, and bearings on the inner face of the cap for the outer ends of 20 the stems.

13. In an engine, the combination with a cylinder, of a rotary valve adjacent the head of the cylinder having a stem, a bearing for said stem, a gear mounted on the 25 stem above said bearing, a cap forming a housing for the gear, and a bearing on the inner face of the cap for the outer end of the stem.

In testimony whereof we affix our signatures in presence of two witnesses.
